JOHANN HEINRICH MEYER, OF MAGDEBURG, GERMANY.

AUTOMATIC CONVERSATION-COUNTER FOR TELEPHONE-EXCHANGE SYSTEMS.

SPECIFICATION forming part of Letters Patent No. 717,755, dated January 6, 1903.

Application filed March 28, 1901. Serial No. 53,329. (No model.)

To all whom it may concern:

Be it known that I, JOHANN HEINRICH MEYER, a subject of the King of Prussia, German Emperor, residing at No. 1^a Gneisenaustrasse, Magdeburg, Germany, have invented Improvements in Automatic Conversation-Counters for Telephone-Exchange Systems, of which the following is a specification.

This invention relates to an automatic conversation-counter for telephone-exchange systems which is installed at the subscriber's station and only comes into operation when the particular subscriber has called up the exchange-office and the desired connection has been made thereby. The counter is not, however, actuated if the desired connection is not made or if the particular subscriber is called up from another station. The operation of the conversation-counter is effected by operating under known form of current-generating means, as by turning the crank of the magneto-machine or other inductor or when calling up by means of a battery by pressing the button in calling the desired subscriber, for which purpose a form of switch must be used consisting in the case of the magneto of a contact-disk that is always connected to the line conductor mounted on the crank or driving spindle of the magneto-machine, which spindle is movable longitudinally in the known manner, and in the second case a contact-bar is mounted on the press-button, which bar in its position of rest is connected to the bell or other signaling device, while on movement of the crank or driving shaft or on depression of the button the disk or bar first comes into connection for a moment with the electromagnet of the counter and then with the magneto-machine. In order that the counting mechanism shall only be operated when the desired connection is actually made, there is arranged at the exchange-office a special switch with relay which is preferably combined with the switch for the attendant's telephones and serves after making the connection between the two subscribers to send a battery-current to the calling subscriber, this battery-current actuating the counting mechanism at that subscriber's station as soon as on turning the crank-spindle of the magneto-machine or on pressing the button the contact-disk or the contact-bar is connected

to the electromagnet of the counter in the manner above described. This current is again interrupted after completion on the counting, for which purpose the armature of the electromagnet of the counter opens an interrupting contact, whereby the relay controlling the counting-current is deenergized, so that the ordinary connection is again made at the exchange-office. A conversation-counter of this kind is shown in the accompanying drawings, in which—

Figure 1 is a front elevation, and Fig. 2 a side elevation, thereof. Fig. 3 shows the switch and the relay at the exchange-office in side elevation. Fig. 4 is an underside view of the switch, and Fig. 5 a plan thereof. Fig. 6 shows the connections of the conversation-counter and magneto-call. Fig. 6^a is a view similar to Fig. 6, but showing a push-button and battery instead of a magneto. Fig. 7 shows the arrangement for electrically actuating the relay at the exchange-office. Fig. 8 shows a detail of the arrangement for calling up by means of a battery.

On the crank-spindle A, Fig. 1, of the magneto-machine or other inductor (which is provided in the known manner with a pin t, that lies in a recess having inclined side surfaces in the hub n of the driving-wheel w) and insulated therefrom is secured the contact-disk L, with which the contact-spring f, connected to the line conductor, is always in engagement. A spring i continually acts to move the crank-spindle toward the left, so that the contact-disk L in the position of rest of the crank-spindle is in engagement with the contact-spring W, which is connected, through the hook-switch V, with the bell W, Fig. 6, or other signaling device. On rotating the crank the pin t first slides along one of the inclined surfaces of the recess until it reaches the outer end thereof, whereupon in the further rotation of the spindle of the magneto the gear-wheel w is driven thereby. Thus on commencing to rotate the crank a displacement of the crank-spindle in the direction of the arrow in Fig. 1 is produced by the pin t acting in opposition to the spring i. The contact-disk L in this displacement first comes into engagement with a contact-piece Z', mounted on a spring Z and connected to the electromagnet C, Fig. 6, of the counter,

then leaves the spring W, slides over the contact-piece Z', and engages at the next moment with the spring J as it leaves Z', so that at the completion of the right-handed movement 5 the inductor is switched into circuit. The above operations are repeated in the reverse order on releasing the crank. The springs W and J must be adjusted in such a manner that in the passage of the disk L from one 10 spring to the other there can be no interruption of the circuit. As soon as the contact-disk L comes into engagement with the contact-piece Z' of the counting mechanism the electromagnet C of the counter is energized, when the battery is thrown in circuit from the central station. On the armature o of the electromagnet, which acts on the ratchet-wheel w' of the counting mechanism by means of the feed-pawl l, is mounted an 15 adjusting-screw x, which in the lowermost position of the armature brings a contact-spring u, connected in the line-circuit, out of engagement with the fixed contact k. Thus after the electromagnet of the counter has 20 been energized as soon as the armature o is attracted and the ratchet-wheel w' of the counting mechanism thereby moved on one unit the circuit is broken by the action of the adjusting-screw x on the contact-spring u. 25 The armature o of the electromagnet of the counter, which has thus been deenergized, is then returned to its original position by the spring z, whereupon the feed-pawl l engages behind the next tooth of the ratchet-wheel w'. 30 If a subscriber after having taken his telephone from the hook is turning the magneto-crank for calling the operator in the telephone-exchange, the current produced by the magneto-armature will take the following 35 path: from the spring J, connected to the one end of the armature, over the disk L, the contact-springs f and u, the contact k and the line a to the electromagnet of the line-drop D, and from the same over the line b and 40 the contact-spring J' to the second end of the armature. The called-line drop will thereby be operated. The operator now inserts the calling-plug B into the calling-jack E, whereby the calling-line drop is cut out and instead of the same the calling system is put 45 into the circuit by moving the reversing hand-lever h of the switch, Fig. 3, to the right. 50 The switch arranged at the exchange-office for switching in the counter-battery after making the connection is combined, in the example shown, with the known Stock's lever-switch for connecting and disconnecting the attendant's telephones. The hand-lever h of this switch, Fig. 3, extends through a slot in a bar 55 p, movable with friction beneath a plate v, a roller r being mounted on the bar p by means of a spring-arm q. The slot in the bar p is of such dimensions that on the reversal of the hand-lever h the said bar is only carried along 60 by the lever when the latter has completed two-thirds of its movement. The roller r acts on the armature s of a relay M, connected in the

circuit of the counter-battery d. On this armature is mounted an arm g, which normally rests on the contact 1. On energizing the relay, however, it rests on the contact 2, connected to the positive pole of the counter-battery, and is provided with an insulating-piece 70 1', which on energizing the relay presses a contact-spring c against the contact 3, connected through the contact-springs 9 and 8 to the negative pole of the counter-battery. The contact-springs 8 and 9 are new and are added to the known lever-switch. The arm g on the armature of the relay M is connected 75 through the conductor 14 to the plug-terminal a' of the calling subscriber, while the contact 1 is connected through the conductor 15, the contact-springs 5 and 4, and the conductor 16 with the plug-terminal a² of the desired 80 subscriber during a conversation. By means of this arrangement it is rendered possible that the counter-battery d shall only come into action on cutting the attendant's telephones out of circuit again. If on switching 85 into circuit the attendant's telephones the hand-lever h is moved to the right out of the position shown in Figs. 3 and 6, the two contact-springs 8 and 9 are brought out of contact with each other and the circuit of the counter-battery is thus broken, so that if on bringing the 90 roller r onto the armature s the arm g thereof engages with the contact 2 no current can flow from the battery to the calling subscriber. If the hand-lever h is moved to the right position, Figs. 3 and 6, each of the four contact-springs 4, 5, 6, and 7 is brought into contact with their respective contact-springs arranged under same, whereby, however, the following 95 springs are put out of contact: 4 from 5, 6 from 7, and 8 from 9. Now the operator in the exchange and the calling subscriber are allowed to speak with each other. The operator calls by speaking into the microphone M². The currents produced thereby in the induction-coil J R² in the known manner are taking the following path: conductor 25, switch B^{1a}, conductor 23, contact 5, conductor 15, contact 1, arm g, conductor 14, terminal a', calling-plug B, line a, contact k, springs u and 100 f, disk L, spring W, hook V, spring y, induction-coil J R', indicator G, telephone F' of the calling subscriber, and back over b b' 10 721 105 26 to the induction-coil J R² and the receiver F² of the operator. The calling subscriber 110 now gives his order by speaking into his microphone M'. After having received the order the operator cuts in the line to the called subscriber by inserting the plug F' into the called subscriber's plug H. If, on the other 115 hand, in cutting out of circuit the attendant's telephones the hand-lever h be again moved to the left, the contact-springs 8 and 9 will be first brought into contact with each other again, whereupon toward the end of the movement of the hand-lever the armature s is again depressed by the roller r. By this means the armature-arm g is brought into engagement with the contact 2 and the circuit 120 125 130 135

of the counter-battery d closed, so that a current will pass from this battery through the conductor 17, terminal K', conductor 11, relay M, conductor 10, contact 2, armature-arm 5 g , conductor 14, and the plug B over the conductor a to the apparatus of the calling subscriber, this current passing via the contact k , the contact-spring u , the contact-spring f , the contact-disk L, the contact-spring W, and the hook-switch V, from which the telephone-receiver is removed, and the contact-spring y to the indicator G, returning to the negative-terminal Z^3 of the counter-battery through the telephone-receiver, the conductor b , the plug 15 B, the plug-terminal b' , the conductor 18, the contact-spring c , the contact 3, the conductor 13, the contact-springs 9 8, and the conductor 12. The relay M is consequently energized and holds the armature s in its attracted position 20 even when the roller r has already left it. By the excitation of the indicator G, which takes place simultaneously so long as L touches the spring W, a tablet therein with the inscription "Please call" will be visible as a sum- 25 mons to the calling subscriber to set his magneto-machine or other inductor in operation. The indicator serves to facilitate the work of the official at the exchange-office. The counting also takes place without employing this 30 official. When the armature of the relay is attracted, the circuit of the counter-battery is interrupted, while the branch of the conductor a^3 , leading to the desired subscriber, is interrupted between the contact 1 and the armature-arm g . The calling subscriber can therefore 35 only come into connection with the required subscriber when the circuit of the counter-battery is interrupted at any place, and consequently the armature of the relay falls down. 40 This takes place, as above mentioned, when the calling subscriber by operating the crank of the inductor brings the contact-disk L into engagement with the contact Z' , so that the electromagnet of the counter attracts its armature, 45 in which operation the adjusting-screw x brings the contact-spring u out of engagement with the contact k . At the exchange-office when the current through the counter is interrupted the relay M releases its armature, 50 so that the armature-arm g rests against the contact 1 again and the contact-spring c is brought out of engagement with the contact 3. On interrupting the circuit of the battery d the line conductor a of the calling 55 subscriber is therefore brought into connection through the plug B, the terminal a' , the conductor 14, the armature-arm g , the contact 1, the conductor 15, the contact-springs 5 4, the conductor 16, and the plug-terminal a^2 with the line conductor a^3 of the desired subscriber, while the line conductor b^3 thereof is connected through the plug-terminal b^3 , the conductor 19, the contact-springs 6 7, the conductor 20, and the plug-terminal b' with the line conductor b of the calling subscriber. 60 The two double line conductors are thus directly connected together, the indicator N

for notifying to the attendant the close of the conversation being connected as a bridge between the lines. The alternate currents generated by the inductor of the calling subscriber thus pass to the station of the desired subscriber and actuate the bell or other signaling device thereof. If the operator intends to help the calling subscriber in calling 75 the called subscriber, he moves the hand-lever h to the right and presses the battery-switch Btg down, whereby the operator's calling apparatus is cut out and the battery d is connected to the conductors 22 and 24. The 80 current will now flow from the conductor K over Btg , 24, 6, 19, b^2 , and b^3 to the called subscriber and from there over a^3 , a^2 , 16, 4, 22, Btg , battery-drop B K to the pole Z^3 of the battery. If the operator will call and re- 85 member the calling subscriber, he presses upon the switch Bta , whereby the battery d is connected to the conductors 21 and 23, and a current will flow from K over 21, 7, 20, b' 90 b to the signaling apparatus W' of the calling subscriber, (the telephone of which is upon the hook,) and from there over V, W, L, f , u , k , a , a' , 14, s , g , 1, 15, 5, 23, Bta , B K back to the negative battery-pole Z^3 . If there is not sufficient room beneath the switch-tables for 95 arranging the relays M, they can be arranged separately from the switch-tables, as shown in Fig. 7, in which case they are actuated electrically instead of mechanically.

On the plate p' of the lever-switch h' is mounted the insulated arm q' , which can act on the spring-contact s' , connected to the conductor 51. To the lever h' is, moreover, secured the movable contact r' , which is insulated therefrom and is electrically connected 100 to the conductor 50. If the lever h' is moved to the right, the contact r' is first drawn away from beneath the spring-contact s' . When the lever strikes against the right-hand end of the slot in the plate p' , the said plate, and 105 with it the arm q' , will be moved to the right. By this means the arm q' depresses the contact s' , which, however, does not come into engagement with the contact r' , since the latter would be previously drawn away beneath 110 the contact s' . The circuit of the counter-battery will not, therefore, be closed. On the other hand, as soon as the lever h' is returned to the left hand into its original position the contact r' is first moved beneath the contacts s' , 115 and then when the lever has reached the left-hand end of the slot in the plate p' the arm q' will also be moved to the left, whereby it presses the contact s' against the contact r' . By this means the counter-battery is short- 120 cut through the relay M³. The armature g' is consequently attracted. As soon as it touches the contact 52 and the end of the arm q' has released the contact s' , so that the latter rises from the contact r' , the circuit of 125 the counter-battery is closed through the conductor leading to the calling subscriber. If the conversation has been counted at the calling-subscriber's station, the battery comes out 130

of action, the circuit is interrupted, and the armature g' of the relay M^3 again rests against the contact 53. The calling subscriber is thus obliged to set his counter in operation, since he cannot call up the desired subscriber in any other way. If the exchange-office does not find the line of the desired subscriber free, although the counter-battery is brought into circuit on cutting out of circuit the attendant's telephones by moving back the hand-lever h' , yet it is immediately disconnected again by withdrawing the plug B from the jack E, so that the relay M^3 is deenergized and the counter-battery cannot come into action when the subscriber in question again calls up the exchange-office. The counting of the conversation takes place after sending the counting-current, as a rule, when the inductor is set in action by the calling subscriber. If this has been commenced, contrary to the regulation, by turning the crank before the summons to ring up has been given by the exchange-office by means of the indicator, the counting takes place as soon as the crank is again released and the contact-disk L slides away over the contact Z' . With such improper working of the inductor there is no calling up of the desired subscriber, since the connection with such subscriber is only made when the counter of the calling subscriber has recorded the connection. The calling subscriber must therefore again set the inductor in action, without, however, thereby actuating the counter again.

The counter-battery is to be of such size that its current is of about ten volts higher pressure than the alternate currents generated by the inductor in calling up, in order that the counting-current shall not be rendered ineffective thereby. A counter-battery of from fifty to sixty volts is generally sufficient. The switch arranged at the exchange-office for connecting into circuit the counter-battery can obviously be also connected to a suitable switch other than the lever-switch shown in the drawings.

When the call is not to be made by means of an inductor, but by a battery, the arrangement shown in Figs. 6^a and 8 is employed. The press-button 36 here acts on a contact-bar 30, which is attached, by means of a flat spring 48, to the block 45, connected to the line by means of the conductor 46. On both sides of the contact-bar 30 are secured contact-springs 32 33, the distance apart of which from the bar is determined by the heads of the screws 34 35, which extend through suitable holes in the springs. The contact-spring 32 normally rests on the contact 31, which is connected, through the conductor 47, with the bell or other signaling device or with the telephone-receiver. On the other side of the bar 30 is arranged the contact 42, which is connected, through the block 43 and the conductor 44, to the signaling-battery W^5 . Beneath the bar 30 is mounted a contact 37, which is secured by the spring 49 to the block 38. The latter is con-

nected, through the conductor 39, to the electromagnet of the counter. Near the contact 37, but insulated therefrom, is mounted a contact 40, which is connected, through the conductor 41, with the return line conductor. In the position of rest the contact-bar 30 makes a connection between the line conductor and the bell or other signaling device or the telephone-receiver. If the press-button 36 is depressed to call, the free end of the contact-bar 30 first slides over the contact 37, connected to the electromagnet of the counter through the conductor 39, then over the intermediate contact 40, connected to the return line conductor, and finally rests against the contact 42, connected to the battery of the bell or other signaling device through the conductor 44. On releasing the press-button 36 the contact-bar 30 comes into engagement with the contacts in the reverse order. The contact-springs 32 33, mounted on the contact-bar 30, are so adjusted that on the transfer of the contact-bar 30 from one contact to the other there can be no interruption of the circuit. The intermediate contact 40 prevents simultaneous engagement of the contact-bar 30 with the contact 37 and the contact 42, and thus also prevents the passage of a current from the battery W^5 for the bell or other signaling device to the electromagnet of the counter. The rest of the apparatus and the method of operation remain unaltered.

I claim as my invention—

1. Telephonic-conversation-counting mechanism comprising a calling-station, a central station and a called station, a current-generating means, a switch, a counter and a current-interrupter adapted to be operated on the movement of the counter, all at the calling-station, a battery, a relay, switches operated thereby and a hand-switch at the central station, a line connecting the calling and central stations and one between the called and central stations, whereby on operating the hand-switch the relay is energized and the battery connected to the line, and calling station, whereupon on operating the switch at the calling-station, the counter is operated and the circuit broken and at the central station the relay released, the battery cut out and connection automatically made between the calling and called stations.

2. Telephonic-conversation-counting mechanism comprising a calling-station, a central station and a called station, a current-interrupter and a counter at the calling-station, a battery, a relay and switches therefor, and a hand-switch at the central station, a line between the calling-station and central station and one between the called station and the central station, said hand-switch upon its movement adapted to make certain connections between the calling-line and the relay-switch points and to operate the relay-switch to complete such connections whereby a current will be sent from the battery through the relay, line and calling-switch, upon the move-

ment of which switch the said current-interrupter is adapted through the counter to break such circuit and thereby automatically cut out the relay and battery and connect the called and calling subscriber, substantially as described.

3. Telephonic-conversation-counting mechanism, comprising a central station having a relay, switches therefor, a battery and a hand-switch in combination with a calling-station, having a current-interrupter, a counter, a current-generating means and a switch for directing the current therefrom whereby on the first operation of the switch to call central, the generated current will be sent through the line and means, upon the release of the switch, whereby a current may be sent from the central station, said switch being adapted when next operated to switch such central-station current through the counter to operate it, said counter when operated being adapted in turn to operate the current-interrupter, as and for the purpose described.

4. A telephonic-conversation counter comprising a calling-station, a current-generating means therein, a switch therefor, means to operate them together, a counter and a circuit-interrupter, a line to the central station, said switch having a contact W, a contact f connected through the interrupter to the line, a movable contact L, and a contact J, connected to one pole of the generating means, the other pole connected to the line, a contact Z connected to the magnet of the counter and a connection from the contact W to the line, whereby on the first movement of the contact L a current generated is sent through the line, and afterward when current is entering the calling-station from the central station, the contact L is adapted, when moved, to send such incoming current through the contact Z and counter and operate such counter and interrupter and then is adapted to send its generated current through J, f over the line, substantially as described.

5. A telephonic-conversation-counting mechanism, comprising a receiver, and an indicator, a connection from the indicator to the line, a switch-contact W and a connection

from the receiver to such contact, a current-generating means, a movable switch-contact L, means to operate them, a contact f, an interrupter, a connection through such contact and interrupter to the line, a contact J connected to one terminal of the generating means, the other terminal being connected to the line, a contact Z, a counter, a connection from the counter to the contact Z and another connection from the counter to the line, but to the opposite line-terminal from the connection from the interrupter, substantially as described.

6. Telephonic-conversation-counting mechanism, comprising a central station, a called station and a calling-station, a counter, a circuit-interrupter adapted to be operated by the counter, current-generating means, a shaft movable lengthwise, means to operate said shaft to so move it, a spring to return it lengthwise upon the release of said means, a contact carried by the shaft, contacts W and f adapted to bear on the disk throughout its movement, a line connection from one pole of the current-generating means, a contact J from the other, a contact Z adapted to be contacted by the disk L before such disk strikes the contact J on its lengthwise movement, the contact f connected through the circuit-interrupter with the line, and contact Z connected to the counter-magnet, whereby when no current is incoming on the line and the shaft-operated current will flow from the current-generating means through J and f and when released circuit will be established from line through f, L, W, and whereby on bringing current in from the line and operating the shaft, line-circuit will be established between f, L, Z and counter, whereupon said counter will be operated and cause the interrupter to open the circuit, as described.

In testimony whereof I have signed my name to this specification in the presence of two subscribing witnesses.

JOHANN HEINRICH MEYER.
